[57] CLAIM

The ornamental design for a dump truck body, as shown and described.

DESCRIPTION

FIG. 1 is a left side elevational view of a dump truck body showing the new design;

FIG. 2 is a right side elevational view thereof;

FIG. 3 is a front elevational view thereof;

FIG. 4 is a rear elevational view thereof; and

FIG. 5 is a top plan view thereof.

The broken lines showing a truck in FIG. 1 are for illustrative purposes only.

FIG 3

FIG 4
